UNITED STATES PATENT OFFICE.

MYRON FRANCIS HILL, OF BOSTON, MASSACHUSETTS, ASSIGNOR OF ONE-HALF TO
EDWARD E. CLEMENT, OF WASHINGTON, DISTRICT OF COLUMBIA.

TELEPHONE-EXCHANGE.

1,253,688.

Specification of Letters Patent. Patented Jan. 15, 1918.

Application filed March 24, 1908. Serial No. 423,051.

To all whom it may concern:

Be it known that I, MYRON FRANCIS HILL, a citizen of the United States, residing in Boston, county of Suffolk, State of Massachusetts, have invented certain new and useful Improvements in Telephone-Exchanges, of which the following is a specification, reference being had to the accompanying drawings, in which similar parts are designated by the same letters of reference.

10 My invention relates to telephone exchanges, and has for its object the reduction of the wiring and apparatus and the resulting simplification of the exchange.

15 My invention consists in the substitution of a few circuits controllable by a large number of subscribers for the individual circuits heretofore used in such a way that any person may control at all times one of the 20 few common circuits. More particularly my invention consists in an exchange in which the subscribers are divided into groups preferably of about one hundred each, each group provided with a number of trunk 25 lines, reaching from the central exchange to short individual circuits, which in turn are connected to the subscriber's station.

For the busiest groups of subscribers fifteen or twenty trunk lines are required, 30 while for suburban groups but a few trunk lines are required, perhaps not more than eight or ten.

For each group the trunk lines are divided into two sets, one of receiving trunk 35 lines and the other of transmitting trunk lines. The receiving trunk lines are connected to a single board of the multiple switch board central station. When any subscriber of a group takes his telephone off from its 40 hook, his individual short circuit is automatically connected to one of the idle receiving trunk lines, and this connection operates an indicator at the board to which the receiving trunk line is connected, informing 45 the operator that a subscriber desires a connection. The operator then finds out the number of the desired subscriber, connects the receiving trunk line to a transmitting trunk line, belonging to the group of the desired subscriber, and automatically causes, 50 by means of a commutator at her board, the

transmitting trunk line to be connected to that subscriber.

The transmitting trunk lines of each group are connected in multiple to all the 55 boards of the exchange. Any transmitting trunk line of a group may be connected automatically to any subscriber of that group under the proper conditions.

In the drawings, 60 Figure 1, represents in diagram view the plan of the circuits of the exchange.

Fig. 2, shows the automatic switches which interconnect the subscribers' circuits and the trunk lines of a group, and the circuits 65 by which they are controlled.

Fig. 3, shows in diagram view the connection of two transmitting trunk lines to two boards of an exchange, and the substitute for a multiple switch board test circuit. 70

Fig. 4, shows a face view of a section of the board, to which the transmitting trunk lines of a group are connected.

Fig. 5, shows in sectional view one form of an indicating spring jack. 75

Fig. 6, shows a vertical sectional view of a different form of an indicating spring jack.

Fig. 7, shows a sectional view of a third modification. 80

Fig. 8, shows a plan view of a transmitting terminal switch, and the circuits by which said switch is controlled.

Fig. 9, shows the commutator outfit of a central office operator by means of which a 85 transmitting trunk line is connected to a subscriber's circuit.

Fig. 10, shows in side view part of the circuit controller.

Fig. 11, shows an edge view of the apparatus which controls the operation of a 90 transmitting trunk line switch.

Fig. 12, shows in side view a transmitting trunk line switch.

Fig. 13, shows a portion of the same in 95 plan view.

Fig. 14 shows an end view of part of the commutator apparatus.

Fig. 15 shows a side view of part of the operator's cord switch with the plug removed. 100

Figs. 16 and 17 are modifications.

Fig. 18 is a detail.

Fig. 19 is a diagram of the telephone switch hook in normal position.

Fig. 20 is a similar view of the hook in actuated position.

Fig. 21 is a diagram of the mechanical line relay in one of its actuated positions.

Fig. 22 is a similar view of the relay in another one of its actuated positions.

10 In Fig. 1, are shown two boards of a multiple switch board exchange to which are connected receiving and transmitting trunk lines. T_8' , T_8^2 , T_8^3 are transmitting switches by means of which the transmitting trunk 70 lines T_1' , T_1^2 and T_1^3 , are connected to short individual circuits, A, A', A'', B, B', &c. To each of these short individual circuits A, A', A'', B, B', &c., are connected subscribers' 75 outfits like that shown in diagram view 20 in A'.

The two wires a and b , of the short metallic circuit are normally connected to bells a' , contact a^2 , switch lever a^3 normally connected, thereto, and back to the wire b .

25 When the telephone a^4 , is switched for use, the circuit is transferred from the bells a' , to the subscriber's telephone a^4 , secondary coil a^{14} , contact a^7 , and switch lever a^8 , temporarily connected thereto.

30 The local circuit including the contact a^7 , primary coil a^9 , transmitter a^5 , battery a^{10} , and contact a^{20} is closed at the same time.

The two wires are open to each other while the switch lever a^8 , is in transit between the 35 contacts a^2 and a^7 . When the telephone is removed from the hook the usual automatic spring device causes the heel contact a^9 , of the switch lever to strike the insulated contact a^8 , on the lever a^{12} , thus grounding the 40 wire b , through the switch lever a^8 , heel contact a^9 , insulated contact a^8 , condenser a^{10} , and ground at G.

The lever is then released and the projection a^{11} of insulating material prevents the 45 contact a^9 from touching the contact a^{12} . When the telephone is restored to its hook, the contact a^{13} insulated from but mounted upon the switch lever a^8 , comes into contact with the lower surface of lever a^{12} , thus 50 grounding the wire a , through the tension spring a^2 . When the hook is released the insulated projection a^{11} , prevents a connection between the contacts a^8 and a^9 . Thus when the rear end of the switch-hook lever 55 a^8 moves downward, the metal at a^8 engages the contact plate a^9 without striking the metal at a^{11} ; and when the rear end of the lever a^8 moves upward, the contact plate a^{13} engages the metal a^{11} without striking 60 the plate a^9 .

The telephone a^4 has a flexible cord support a^{15} , secured to a contact spring a^{16} , adapted while the telephone is suspended therefrom to make contact with the contact 65 point a^{17} , thus closing the circuit of the bells

a' , in a shunt around the telephone circuit a^4 , a^{14} , while the telephone is switched for use. The purpose of this device will be seen later. The wires a , b , of the short individual metallic circuit, are connected by multiple 70 branches c and d to each receiving switch R_3 and transmitting switch, of the group to which the subscriber belongs. These connections are shown in Figs. 1 and 2. The form of switches in Fig. 2 is preferred. 75 Those in Fig. 1 are simplified to better illustrate line circuits.

The branches c and d , are connected to the contacts c' and d' , on each switch. On each switch are ring contacts c^2 and d^2 in 80 juxtaposition to the contacts c' and d' , and adapted to be connected thereto by the contacts c^3 and d^3 respectively, mounted upon the circuit closing lever of each switch. To the ring contacts c^2 and d^2 , are connected 85 two wires c^4 , d^4 of the metallic circuit of each trunk line.

The connection between a subscriber's metallic circuit and a receiving trunk line R_t is effected as follows:—When the subscriber 90 removes his telephone from its hook thus switching it for use, a circuit is closed from the ground G, condenser a^{10} , contacts a^9 and a^8 , switch lever a^8 , line conductor b , to the automatic sub-central switches, individual 95 branch wire e , coil e' , contacts e^2 , conductor e^3 , common to all the subscribers of the group, conductor e^5 , to the central exchange, current generator D, and ground G.

Current from the battery B energizes the 100 relay e^4 , over the circuit including relay e^4 , resistance e^{11} (about equal to that of the magnet e^2), contacts e^{19} , e^{20} , resistance e^{17} , thus releasing the escapement e^{16} of the weight or motor e^{18} .

The motor e^{18} propels at a regular speed the shaft f , upon which are mounted the receiving and transmitting switches R_3' , R_3^2 , T_8' , and T_8^2 .

A resistance e^{17} graduates the amount of 110 current supplied to the relay e^4 .

The alternating current on the circuit just traced, energizes the coil e' , as shown in Fig. 21, which produces a change in the circuits, so that the subscriber's line will secure 115 a connection to one of the receiving trunk switches but no other. As the coil e' is energized, its core attracts the armature of lever e''' . Since the upper end of lever e''' is in contact with the contact plate e^2 mounted on 120 the lever e^{18} it slides on the plate which acts as a cam lifting the lever e^{18} until the upper end of the lever e''' leaves the plate e^2 . Then the lever e^{18} drops again, its insulating plate e^{181} resting on the upper end of the 125 lever e''' , and the metal of the lever resting against the rear of contact e^{19} . At the same time, when the coil e' attracts the lever e''' , a contact portion on the front of contact e^{18} engages the spring contact e^{20} , and the rear por- 130

tion of the contact e^{29} is withdrawn from contact with the back contact e^{25} . From this mechanical operation it will be seen how the following electrical circuits are established; 5 their object being to connect the subscriber's line to a receiving trunk line exclusive of any other trunk line connection.

From one pole of battery B by way of magnet e^4 , resistance e^{11} , of which there is 10 preferably one individual to each subscriber contacts e^{38} and e^{39} now closed, wire e^{13} , branch wire e^{14} , of switch Rs^2 for example, contact e^{15} , individual to the subscriber's circuit, (see Fig. 8) brush contact i' , coils 15 i^2 , of the magnet operating the circuit closer h , wire i^3 , brush contact i^4 , ring contact e^{16} , common to the sets of contacts of all the subscribers of the group, wire e^{17} , containing contacts e^{16} normally closed, there being 20 a separate wire e^{17} and separate contacts e^{18} , for each receiving switch, wire e^{19} , to battery B.

The same circuit might be traced through 25 any other receiving switch belonging to this group in case its traveling arm and contact brushes reach the subscribers' terminals first.

The sets of contacts belonging to each subscriber are so arranged with relation to 30 the normal position of the circuit closers h of the various switches, that no two circuit closers will be in position to make contact with the subscriber's line simultaneously.

To effect this the sets of contacts of a 35 subscriber's line, line a b for example, are arranged in the same vertical line, while the normal positions of the circuit closers h are arranged spirally, or at different points around the shaft f .

40 Presuming that the circuit closer h and switch arm h' , of the switch Rs^2 , make connection with the contacts of line a b , the coils i^2 of the magnet will attract the armature h^2 , pivoted at h^3 , operating the circuit closer h so that the contact e^3 crosses the 45 contact e^1 and e^2 , the contact d^3 crosses the contacts d^1 and d^2 , and the contact i^7 makes connection with the individual switch board contact e^{21} , closing the following parallel 50 circuit:—

From one side of the coils i^2 through wire i , contact i^7 , contact e^{21} , branch wire e^{22} , wire e^{23} , coil e^{24} , individual to each subscriber, to battery B. The rest of this circuit is the same as previously traced over wire e^{19} .

The coil e^{24} when energized opens the temporarily closed contacts e^{38} and e^{39} by lifting the armature. This releases the armature and contact e^{39} by removing the stop contact e^{38} which has been engaged with the contact e^{39} , so that it falls back to its normal position except that it does not strike contact e^{25} on account of the insulated back 65 stop e^{47} interposed by the lifted armature,

as shown in Fig. 22. When e^4 is deenergized by the retraction of lever e''' of magnet e' , the shaft f stops.

The contacts e^2 are opened before the contacts e^3 and d^3 of the circuit closer h cross 70 connect the contacts e^1 , e^2 , and d^1 , d^2 .

The contacts e^{25} and e^{39} when held open, as described prevent a transmitting switch Ts' , or Ts^2 from making connection with this line. 75

Thus it will be seen, after any subscriber's circuit a , b , has been connected to a receiving switch, Rs^2 for example, no other receiving switch Rs' , or transmitting switch Ts' , or Ts^2 , can be connected to it. 80

The circuit of the subscriber's line a , b , when thus connected is continuous through the two limbs c^4 and d^4 of the receiving trunk line Rt^2 to the central station (see Fig. 1,) where these limbs are connected, 85 through intermediate switch apparatus controlled by the operator, to the two contacts c^6 and d^6 of a connecting plug P.

If the subscriber's line a , b , had been connected to any other trunk line of the group, 90 Rt' for example, it would have been connected to another plug, through another set of switching apparatus controlled by the same or another operator, who may be stationed at board No. 2, or elsewhere. 95

If a subscriber of another group had taken his telephone off his switch, subscriber No. 309 for example, connected to line B^2 , he would have been connected to a receiving trunk line, Rt^3 for example, and thus connected to a plug P controlled by an operator at board No. 3, as shown. 100

It will be noticed that the short individual metallic circuits A , A' , A^2 and A^3 belonging to subscribers No. 201, No. 241, No. 105 242 and No. 243 may be connected through receiving trunk lines Rt' , and Rt^2 , to switch plugs P under the control of an operator at board No. 2. These subscribers' lines are but a few of the large number, one hundred 110 for example, which may be connected through these switches Rs' and Rs^2 . There may be additional switches Rs and corresponding additional trunk lines Rt , to which the same subscribers' lines may be connected. 115

In like manner the short individual metallic circuits belonging to subscribers No. 309, No. 310, No. 311, No. 322, and No. 313 lettered B^4 , B^5 , B^6 and B' and B may be connected through one or more receiving 120 switches Rs^3 to one or more receiving trunk lines Rt^3 , and thence to plugs P at central. The subscribers' lines referred to are but a few of the number that may be employed. Preferably however there are one hundred 125 or less subscribers' lines adapted to be connected to plugs P at board No. 3.

In like manner I divide all the subscribers of the exchange into groups of one hundred or less each, and so connect the sub- 130

scribers' lines of each group to switches and trunk lines that the lines of each group may be connected to any section of the central switch board preferably that individual to the group. All the subscribers having numbers under one hundred are connected to board 0, all subscribers numbered 100 and over and under 200 are connected to board No. 1, all subscribers numbered 200 and over and under 300 are connected to board 2, and so on. This relation between the number of the subscriber and the number of the board at central is not necessary but is more convenient. Except for convenience' sake this arrangement is entirely unnecessary. And the system will work quite as well if the receiving trunk lines are distributed among the various boards so as to even up the work of the operators. Receiving trunk lines from several groups of subscribers might be connected to a single board under the supervision of a single operator. When applied to an exchange system in which the multiple switch board feature is not used all the trunk lines would be supervised at a single board.

The groups of subscribers may if desired have any desired number of circuits as long as each group has a different designating character from any other group.

The connection between a subscriber's line A and a receiving trunk line Rt^2 has been described. A complete metallic circuit is established through the subscribers' conductors a and b to the trunk line conductors c^4 and d^4 . This circuit is normally completed through the contact springs c' , d' , contact springs c^8 , d^8 , annunciator c^{13} , and impedance coils d^{13} , leading to an alternating current generator CG which will be described later. There is a separate generator for each receiving trunk line. The current is of such a character that it will energize the coil c^{13} , causing the annunciator c^{13} to attract its flap in such a way as to display its signal, informing the operator that a call has been sent in from some subscriber of the two hundreds group over the trunk line Rt^2 . Incidentally the pairs of contacts c^{12} and d^{12} are closed but at present this has no function. These contacts are closed by the two armatures, one at each end of the coil e^{13} being drawn up against the front contacts c^{12} and d^{12} .

When the operator sees the annunciator c^{13} display its signal she lifts the plug P from the base P' upon which it is normally supported causing the release of contact springs c' and d' so that they may come into contact with the contacts c^{10} and d^{10} as shown at board No. 3. This connects the two trunk line conductors c^4 and d^4 to the operator's telephone set P^* , constructed in the usual manner, supplied with a transmitter current from battery B. Thus a conver-

sation circuit is established from the subscriber to the operator. The subscriber informs the operator with whom he desires to be connected, subscriber No. 322 for example.

The operator then inserts the plug P into the spring jack of an outgoing transmitting trunk line, Tt^3 for example, adapted to be connected through a transmitting switch Ts^3 to the short outlying metallic circuit of subscriber No. 322. This connection is established automatically as will now be described.

It will be noticed that when the plug has been withdrawn from its resting place the contact springs c' and d' have left the contact springs c^8 and d^8 which in turn have separated from and released the contact springs c^9 and d^9 so that the latter make connection with the normally disconnected contact points c^{11} and d^{11} electrically connected to the commutator contacts c^{14} and d^{14} . Thus the two contacts c^9 and d^9 of the plugs P are connected through the contact springs c^9 and d^9 , contacts c^{11} and d^{11} , to the commutator contacts c^{14} and d^{14} . In connecting to a transmitting trunk line the operator has connected to the group to which the called subscriber belongs. All that remains for the operator to do is to select the particular subscriber of the group to which the trunk line is to be connected. This she accomplishes by means of the commutator C, keyboard C', and plug P*. These elements make up her commutator outfit. Upon the cylinder C which is made of insulating material in the modification which is being described, are mounted contact strips g' of variable lengths of conducting material.

These contact strips g' are so arranged with relation to the contact springs c^{11} that but two strips are adapted to touch all the contact springs c^{11} , three strips adapted to touch nine contact springs, four strips adapted to touch eight contact springs, and so on, so that each contact spring c^{11} is adapted to be connected through the strips g' to the contact spring c^{14} a different number of times.

The contacts d^{17} bear the same relation to the strips g' as do the contact springs c^{11} . For groups of one hundred subscribers there are ten contact springs c^{11} , ten springs d^{17} , and eleven strips g' normally disconnected therefrom. The contact springs c^{11} and d^{17} are connected to insulated cross bars c^{18} and d^{18} as shown. The plug P^* grounded at G is adapted to be connected to a single cross bar c^{18} and a single cross bar d^{18} thereby connecting them both to ground. In connecting to subscriber No. 322 the operator places the plug P^* upon the cross bars 2 at their junction and rotates the cylinder once in the direction of the arrow.

The cylinder is rotated in such a direction

that each strip g' touches a contact spring or springs d^{17} and after leaving these springs touches one or more contact springs c^{17} . The last strip g'' which passes under all the contacts c^{17} and d^{17} is so formed that it touches the contact spring c^{17} while it touches the contact spring d^{17} , thus simultaneously cross connecting these springs. When the plug P^6 has been placed upon the cross bars 2 of the sets of cross bars c^{18} and d^{18} , and the cylinder C rotated once as described, the contact springs c^{17} and d^{17} connected to those two cross bars are connected to the contacts c^{14} and d^{14} by the four longest strips successively as described, establishing the following circuits, which may be traced upon Figs. 1 and 2:—from ground G through the alternating current generator D, a supply wire e^8 reaching to the sub-central to which line No. 322 is connected, thence through contacts e^{31} , condenser e^6 to the relay e^9 , wire e^{32} , including the set of normally closed contacts n , (the order of the relays and contacts being immaterial), thence by trunk line conductor d^4 , to spring jack contact d^5 , plug contact d^6 , contact spring d^9 , contact point d^{11} , wire d^{10} , contact d^{14} , one of the contact springs d^{17} , the one connected thereto by the cross bar 2, of the set designated d^{18} , thence by way of plug P^6 connected thereto, to ground at G. This circuit is made and broken four times by the strips g' of the commutator. The relay e^9 is energized four times. Referring now more particularly to Fig. 2, it will be seen that when the relay e^9 is energized it accomplishes two functions, in connection with the selecting and controlling apparatus there shown, which is located at the sub-central station to which the called line is connected.

Not only does it actuate the ratchet movement m^8 of the units switch but it actuates the circuit controller C². When the armature of relay e^9 is drawn down, its heel e^8 forces the link e^8 upward, which in turn tilts the rocker e^{34} against the offset m^8 . This offset is rigidly connected to the ratchet wheel operated by the pawl m^8 and resists the rocker e^{34} , so that the rocker which is pivoted on the pawl m^8 lifts the pawl upward. As seen in Fig. 10, it catches the next tooth of the ratchet wheel and when the relay e^9 is deenergized, the controller C² is advanced one step. With it travels the offset m^8 , which travels downward, and no longer resists any oscillations of the rocker e^{34} , and this operation is not repeated.

This local circuit is closed four times as stated. The first time that the magnet e^9 is energized, the circuit controller C², closes the contacts n' , n^3 and n^6 through the respective contact plates. The operation of the circuit controller C² by the second and third closing of this circuit is prevented as de-

scribed. The functions of these sets of contacts will shortly be described.

When the circuit is closed four times the relay e^9 operates the ratchet mechanism m^8 , propelling the contact arm m^9 , around to contact No. 2 on the units switch m^{10} .

As has been described after strip g' has left a contact spring d^{17} it makes contact with a spring c^{17} , grounding the "c" side of the circuit as follows:—

From ground at G, current generator D, supply wire e^8 , contacts e^{31} normally closed, condenser e^6 , relay e^9 , contacts n^8 , closed as described, trunk line conductor c^4 , jack contact c^5 , plug contact c^6 , contact spring c^9 , contact point c^{11} , commutator contact c^{14} , strips g' , contact spring c^{17} connected to bar c^{18} numbered 2, plug P^6 , and ground G. This circuit is also energized four times.

The relay e^9 therefore attracts its armature four times thus actuating the ratchet mechanism m^{11} and propelling the contact arm m^{12} around to contact No. 2 of the tens switch.

The fourth time that the circuit is closed, the relays e^7 and e^9 attract their armatures together and thus by means of the heels e^8 and links e^9 force upward both ends of the rocker e^{34} , forcing the pawl m^8 upward so as to catch the next tooth of the ratchet n^{11} . When the relays are deenergized the rocker and pawl are released, and operate the controller another step, bringing it to its third and last position. Thus it opens the contacts n^1 and n^3 and closes contacts n^4 and n^5 by altering the position of the respective contact plates n , n^3 , n^4 , n^5 . It is to be noted that the pawl m^8 acts on its back stroke and not on its forward stroke. Its back stroke in the diagrammatic illustration of Fig. 2 is the downward stroke, but this showing is for convenience of diagram only, since in the practical apparatus shown in Figs. 10 and 11 the back stroke of pawl m^8 is an upward stroke.

The closing of contacts n^5 establishes a circuit from the grounded direct current generator D³ over the supply wire e^{31} through the restoring magnet M⁴ to the trunk line conductor c^4 . When this line is connected to ground by a subscriber or by an operator, the magnet M⁴ attracts its armature m^{17} and by means of mechanical connections, m^{18} for example, withdraws the detents m^{19} and m' permitting all the switching apparatus to be restored to its normal position.

When the armature m^{17} is attracted the insulated wedge m^{20} opens the contacts e^{31} and e^{33} . This prevents relay e^7 for example, from being operated while the circuit controller C² is returning to its normal position. The magnet M⁴ being operated whenever the "c" side of the conversation circuit is directly grounded is operated when a

switch board operator closes contacts c^{19} , for example, or whenever a subscriber hangs his telephone receiver upon its switch thereby causing the contacts a^{18} and a^{12} to come into electrical connection, grounding the conductor a directly through spring a^{21} . When the armature m^{17} is attracted by the restoring relay M^4 , it closes the set of contacts m^s , grounding the circuit including relay M^4 through wire m^2 and three branch circuits, one branch m^4 containing contacts n^s closed except when the controller C^2 is in its normal position shown, a second branch m^5 containing contacts m^{61} closed except when the ratchet m^8 is in its normal position, and the third branch m^7 containing contacts m^{100} closed under similar conditions. The contacts m^{61} and m^{100} are closed when the cleft wheel attached to the ratchet carries the cleft beyond the contact spring. As long as anyone of the three branch circuits is closed while restoring, the relay M^4 will keep all the detents m^{17} , m^{19} , and m^s , withdrawn from their appropriate ratchets, thus insuring a return of all the switches to their normal position.

Therefore whenever a subscriber hangs up his telephone the apparatus controlling a transmitting switch is restored.

80 To return now to the manner in which this switch apparatus controls the operation of a transmitting trunk switch, Ts' .

The first step forward of the controller C^2 closed the set of contacts n^s as described. 85 This closes the following circuit including magnet e^4 —battery B, magnet e^4 , resistance m^{14} , wire m^{15} , contacts n^s , wire m^{16} , wire e^{19} , back to battery B. This magnet e^4 at once releases the escapement e^{46} causing the 90 shaft or arbor f to rotate under the influence of the motor e^{38} , so that the transmitting switch Ts' rotates with the shaft, and is ready to close any circuit under the control of the units and tens switches.

45 When the contacts n^4 are closed as has been described, and when the arms m^9 and m^{12} rest upon the contacts 2 of their respective switches representing subscriber No. 22, the following circuit is established:—arm 50 m^9 , contact 2, wire m^{21} , contact e^{40} , of the transmitting switch Ts' , contact i^s , mounted upon but insulated from the switch arm h' , wire i^s , coils i^2 , thence by way of wire i , to the contact i^s , contact e^{15} of the switch, 55 wire e^{41} , pair of contacts e^{25} , e^{39} , open while the line a b is connected to any of the switches, resistance e^{11} , battery B, wiping contact e^{42} , the conducting shaft f , switch lever h' , contact i^s , mounted upon and electrically connected thereto, ring contact e^{16} , conductor m^{22} , contact 2 on the switch m^{13} , contact arm m^{12} of the switch, contacts n^4 now closed by the circuit controller C^2 by the contact plate back to the contact arm m^9 .

60 This circuit may be closed only when the

switch arm h' , of the transmitting switch Ts' comes into electrical connection with the set of contacts belonging to the line a b of the subscriber No. 22 called. For the purposes of illustrating the manner in which 70 a transmitting switch establishes a connection between a trunk line and a subscriber's line, the line a b is represented as belonging to subscriber No. 322 for example, and the group of switches Ts' and Ts^2 may be regarded temporarily as representing the automatic sub-central of the 300 group. When therefore the above circuit is established the armature h^2 of the switch Ts' is attracted 75 causing the contacts c^s and d^s to cross connect the contacts c^s and d^s with the ring contacts c^2 and d^2 respectively. A circuit is thus established between the subscriber's line and the transmitting trunk line. Another transmitting switch Ts^2 is controlled 80 by another trunk line Tt^2 , the local circuits of which are not shown but which are the duplicates of those connected to and controlled by the trunk line Tt' . It has been described how an operator has caused a connection between a transmitting trunk line Tt and a called subscriber. It is necessary 85 that the operator should know that this circuit has been established.

When the lifting of the plug caused the 90 separation of the contacts c^s and d^s from the contacts c^2 and d^2 , the coil c^{18} released the armature opening the contacts c^{12} and d^{12} . Having operated her commutator as has already been described she tips her commutator piece P^2 pivoted at P^3 so that the insulated arms P^4 connect the contact springs c^s and d^s with the contact springs c^9 and d^9 and at the same time disconnecting the contact springs c^s and d^s from the contacts c^{10} and d^{10} , establishing the following circuit:—from the supply current generator CG over 100 the wires c^{15} and d^{15} , high resistances or impedances and coils c^{18} and d^{18} , contact springs c^s and d^s , contact springs c^9 and d^9 now connected thereto, plug contacts c^6 and d^6 , jack contacts c^5 and d^5 , of the transmitting trunk line Tt^2 , through the contacts of the transmitting switch Ts^2 as described, to the subscriber's line connected thereto. When the trunk line is connected to the subscriber's line the coil c^{18} attracts the armature, closing the contacts c^{12} and d^{12} . The armature or flap of the coil c^{18} informs the operator that the trunk line has been connected as desired. If connected, the current from the wires c^{15} and d^{15} operates 110 the call device a' until the subscriber removes his telephone receiver from its hook, 115 switching the call device out of circuit. 120 When the contacts c^{12} and d^{12} are closed 125 as described the receiving trunk line con- 130

ductors c^4 and d^4 are connected through the plug contacts c^8 and d^8 to the conductors c^4 and d^4 of the transmitting trunk, thus establishing a complete circuit for conversation. As long as this circuit remains intact the indicator c^{13} informs the operator that the lines are "busy."

If however, a called subscriber is already connected to another transmitting or receiving trunk line, this trunk line described can not establish connection with him, for the reason already stated in connection with the description of the magnets e' , e^{24} , and the levers e''' and e^{38} . The operator noticing that the called subscriber is busy informs the calling subscriber to this effect, and he may drop his receiver without hanging it upon its hook and wait for the called subscriber to finish his engagement. Dropping his receiver in this way leaves it hanging upon the cord a^{15} thus causing the spring contact a^{16} to come into contact with the contact a^{17} closing the circuit of the call device a' in a shunt around the telephone set.

When the busy called subscriber's business is over his line is automatically connected to the calling subscriber's line without the intervention of the central operator, and both subscribers are called up automatically.

This automatic connection depends upon the condition of the circuit of the called subscriber. As long as it is connected elsewhere the contacts e^{25} are open. When this connection is dissolved the contacts e^{25} are closed the transmitting trunk line switch T_s is operated, closing the circuit between the trunk line and the subscriber's line, energizing the coil c^{13} of the operator's outfit at central, causing this trunk line to be connected to the receiving trunk line, to which the calling subscriber is connected through the contacts c^{12} and d^{12} , causing a current from the supply generator CG to actuate the call device a' , polarized bells for example, of the calling subscriber. At the same time the operator is informed of this connection by the attracted flap of the indicator c^{13} .

The operator may at any time by closing the pairs of contacts c^{20} and d^{20} by means of normally open key contacts cut her telephone into the circuit, to determine by listening in, the condition of the line, or to talk with either subscriber.

The indicator c^{13} indicates "busy" as long as a circuit remains established, but as soon as a circuit is opened by the operator or either subscriber in disconnecting the circuits and grounding the b -limb, this indicator releases its flap, indicating the disconnection to the operator.

When a subscriber hangs up his telephone and the restoring relay M^4 attracts the armature m^{17} which releases the ratchet mechanism of the three switches m^{13} , m^{10} and C^2 as described, the plate n^4 opens the contacts

n^4 thereby releasing the armature h^2 of the transmitting switch T_s so that this switch disconnects the subscriber's line a , b , from the transmitting trunk line T_t^4 . The weight of the armature h^2 causes the catch h^3 to become engaged with a detent h^4 which causes the arm h to be carried around again, by the shaft f which is turning under the influence of the motor e^{36} . When the transmitting switch closed the circuit between the subscriber's line a , b , and the trunk line T_t^4 , the contact i^7 coming into contact with the contact e^{21} closed a parallel circuit from the wire i' , through the relay e^{24} to the battery B, opening the contacts e^2 and e^{25} , and e^{39} .

The opening of contacts e^2 prevents the subscriber from getting a different connection while connected with. The opening of contacts e^{25} , and e^{39} prevents another trunk line T_t from being connected to the same subscriber, so that while two subscribers are connected together for conversation by an operator their circuit can not be interrupted or interfered with by another subscriber or any other operator or the same operator over another trunk line. When the operator who has established the circuit closes the contact c^{19} or when either subscriber hangs up his telephone, the "c" side of the established circuit is grounded thereby restoring the transmitting switch apparatus, as described by means of the relay M^4 , and at the same time establishing a circuit from the grounded current generator D^8 , over the supply wire e^{51} , relay M^8 , to the wire c^4 of the receiving trunk line R_t which has been connected to the calling subscriber. The relay M^8 attracts its armature e^{44} , which causes the insulating wedge e^{45} to open the normally closed contacts e^{18} , thereby cutting off the current from the coils i^2 of the receiving switch magnet, so that when the "c" side of the circuit is grounded as described the receiving switch as well as the transmitting switch is released, and by assuming its normal position disconnects the calling subscriber from the receiving trunk line R_t .

Summing up the operations already described they are briefly as follows:—Referring to Fig. 1, subscriber No. 201 for example, desires connection with another subscriber No. 322 for example.

Subscriber No. 201 removes his telephone from its switch lever thus establishing a connection over a receiving trunk line R_t^2 for example, to the operator at board No. 2 to which the receiving trunk line is connected. The trunk line indicator c^{13} indicates the call, and the operator removes the plug P from its resting place thus introducing the operator's telephone set into the trunk line and restoring the indicator c^{13} to its normal condition.

The subscriber in the usual manner, in-

forms the operator that he wishes to talk with No. 322. The operator thus connects the trunk line plug to a transmitting trunk line Ts^3 for example, at a trunk switch section numbered "3", and by operating her commutator outfit causes that trunk line to be connected to the desired subscriber. She does not select a transmitting trunk line in use at another board on account of a multiple switch board "busy" test which will be described later. The operator then turns her cord switch lever P^2 and gives her attention to other calls. The indicator c^{13} at once indicates whether the desired connection has been established and if it has been, the called subscriber's bells are automatically rung. If the called subscriber is busy, the calling subscriber may wait with his telephone at his ear, for the desired connection, or he may drop his telephone and return to his work, in which case, when the called subscriber is through the connection between the called and the calling subscriber is automatically established and the bells of both rung. When either subscriber hangs up his telephone, he disconnects the entire circuit, and the indicator c^{13} at central releases its flap, informing the operator of the disconnection. If both subscribers should by accident fail to operate the restoring apparatus of the sub-central switches, the operator may, as soon as she ascertains this fact by listening in, restore the apparatus by closing the contacts c^{19} .

Fig. 3 shows a test system which may be used with my invention, although it is obvious that any suitable test system may be used in its place. Two boards are shown, board 2 and board 3. At each board is a spring jack J , for each of two transmitting trunk lines Tt^2 and Tt^3 . Each jack contains the contacts c^5 and d^5 already described, and a third contact j . The test contact j of all the jacks connected to a transmitting trunk line are connected together by a test wire j^2 . Each contact j is connected to a test battery J' through individual coils or lamps j' , and the other pole of the test battery is connected to a third contact J^2 on the plug P of each receiving trunk line. The plug also has contacts c^6 and d^6 already described. The contacts in Fig. 3, are somewhat differently arranged from the contacts in Fig. 1. This arrangement lies within the skill of the electrical engineer. When a plug is inserted in a jack as shown, a circuit is established from the battery J' over wire j^4 to the contact j of the jack connected to, by way of wire j^2 to the contact j of all the other jacks of the line, thence in series from the contact j of each jack through the coils or lamps j' of each jack, to the test battery J' .

In Fig. 5, is shown one form of the jack J . This jack has a test contact j , the two

line contacts c^5 and d^5 mounted upon the insulated support of an incandescent lamp j' , but insulated therefrom. This lamp j' is a small lamp of the Edison or any other type, and is mounted to the rear of the switch hole and just beyond the reach of the plug P . Each lamp is preferably provided with a reflector j'' adapted to reflect the light strongly out of the switch hole of its jack, and out of no other switch hole. The reflector may be mercury on the glass itself, and a projecting tube j''' provided to exclude the light from other jacks.

In Fig. 6 is another form of jack. In this figure the lamp j' is inclosed in a long reflecting or non-reflecting cylinder j'' adapted to exclude the light from other jack holes. The jack contacts c^5 and d^5 and j may be mounted in any suitable way. In Fig. 7, is a third form of jack. In this jack is a coil j^8 having an aperture j^9 to permit the passage of light from one or more lamps j^{10} with reflectors j^{11} . The lamps and reflectors, one or both, may be individual to each jack, or common to two or more jacks, and should be constantly burning, so that normally the jacks are lighted. When however, the coil j^8 is energized by a closed test circuit as described, the core j^{12} attracts the magnetic finger j^{13} , attracting the flap j^{14} , shutting off the light from the jack hole, rendering it dark, which in this form of jack, indicates the line to be "busy".

I prefer however the forms shown in Figs. 5 and 6. Although I show this jack for a busy test, that is, to show that a subscriber is to begin conversation, that a conversation is in progress, or that it is over, it is obvious that it may be used for other purposes, that is, for calling, for clearing out, for trunk line signal work, and various similar purposes.

In Fig. 4 are shown a number of jacks, three of which indicate "busy." This is a section of one of the switch boards to which all the transmitting trunk lines of group No. 2, are connected. By inserting a plug in any one of these jacks, the operator controls a connection between a transmitting trunk line and any subscriber of the group.

The switch board is divided into sections similar to this. To each section are connected the transmitting trunk lines of a different group of subscribers, and each section is marked with the appropriate number of the group.

It has already been described how a transmitting switch is operated. Fig. 8 shows more completely the circuits by which this is accomplished. This switch shows in plan view the sets of contacts of a hundred subscribers. Upon the switch are ring contacts c^2 and d^2 common to all the subscribers of the group and connected to the trunk line

conductors c^4 and d^4 , as shown in Figs. 2 and 12. The line wires a b of each subscriber are connected to a different pair of contacts c' and d' .

5 The contacts e^{21} and e^{15} are connected to the wires e^{22} and e^{23} and e^{41} respectively, there being a different set of those wires for each subscriber as shown. There are 10 contacts e^{16} , one of these contacts being common to 10 subscribers. Each contact e^{16} is connected to a contact upon switch m^{13} . The contact e^{16} numbered 0 is connected to the contact marked 0 upon the switch m^{13} . The contact e^{16} numbered 1, is connected to the contact m^{13} numbered 1, &c. The contacts e^{40} are connected to the contacts of the switch m^{10} . Contacts e^{40} numbered 0 are connected to contacts 0 of the switch. Contacts numbered 1 are connected to contact No. 1 of the switch, &c. The set of contacts belonging to each subscriber comprise individual contacts c' , d' , e^{21} , e^{15} and e^{40} . The ring contacts c^2 and d^2 are common to all the subscribers connected to the switch. Each contact e^{16} is common to a different set of 10 subscribers. Contact 0 for example, is common to subscribers 0 to 9 of the group. Contact 3, for example, is common to subscribers 30 to 39 of the group, &c., so that the switch m^{10} selects the unit of a subscriber's number and the switch m^{13} selects the tens thereof. For each subscriber there are separate contacts e^{25} and resistance e^{11} .

The functions of the circuits and apparatus have already been shown in connection with Figs. 1 and 2.

Fig. 9 shows the operator's commutator outfit already described or illustrated in diagram in Fig. 1. Upon a plate of insulating material C^9 are mounted cross strips of conducting material d^{18} . Through each strip d^{18} project push buttons C^{10} , so mounted as to slide up and down through the strip and through the support C^9 . The strips d^{18} are separated from each other by insulating material C^{11} . Each push button C^{10} has around its neck a spring C^{12} , one end of which is soldered to the push button and the other end soldered to the strip upon which the push button is mounted. This soldering is not necessary but is preferred on account of the good electrical connection which results therefrom. The lower end of each push button is provided with a point and hollow portion C^{13} and when a button is pressed down as shown at C^{14} it separates two conducting bars C^{15} and C^{18} thereby separating them and then by means of the hollow described permits them to return almost to their normal position, holding the push button in its operative position. When another push button is depressed and the bars are again separated this push button C^{14} is released and the other one is held in its place. If the same push button is again depressed

it will spring back as far as the notch C^{13} and there be held a second time. The bars c^{18} are at each end mounted upon but insulated from a support C^{16} , which is connected to the insulating plate by toggle-joints, C^{17} . Thus these bars with their support form a kind of gridiron. The mounting of but one corner of this gridiron is shown but the other three corners are similarly mounted.

The conducting bars C^{15} are at both ends mounted upon and electrically connected with a support C^{181} which is mounted by means of toggle-joints C^{19} upon the insulating plate C^9 . A cord C^{22} attached to the toggle joints C^{19} , running over the pulley C^{24} , and connected through a spring C^{25} to a weight C^{20} , holds these gridirons in their normal position with the post C^{26} touching the toggle-joints, to keep them in a normal position.

Pivoted upon the bar C^5 is a lever C^{21} , one end of which is pivoted to the movable bar C^{181} and the other end of which carries an insulated stop C^{22} . Against this stop normally rests a stud or roller C^{23} , secured to the commutator wheel C , holding the commutator in its normal position. When a push button C^{14} is depressed it moves the bars C^{15} mounted upon the cross bars C^{18} which in turn causes the lever C^{21} to remove the stop C^{22} from beneath the roller C^{23} , releasing the commutator wheel C . A key C^{24} with studs C^{25} causes the friction clutch C^{26} to turn on its axis C^{27} and by means of the spring connection C^{28} causes the commutator wheel C to turn in the direction of the arrow. As the bar C^{181} returns at once to its normal position when a push button has completed its downward movement, the catch C^{22} is restored to its first position so that when the commutator C has completed a rotation the stud or roller C^{23} will prevent it from turning any farther. The shaft C^{27} may be used in common for several or all commutators, and is regulated to prevent a too rapid motion of the commutator. The commutator wheel C is mounted loosely upon the shaft C^{27} but prevented from longitudinal movement. The shaft C^{27} is rigidly connected to the key C^{24} .

Upon the body of the commutator C are mounted the posts or rods g' adapted to cross connect the strips c^{14} and d^{14} with the contact springs c^{17} and d^{17} respectively. The last rod g'' to pass under the springs is so wide as to electrically connect all of the springs simultaneously to the strips c^{14} and d^{14} . The rods g'' are double, and have cuts so that one rod affects or strikes only spring contacts c^{17} , and the other rod strikes contacts d^{17} . The rods g'' are so related to the springs that all the springs c^{17} and d^{17} strike and make contact with their respective strips at the same time.

The rods g' , g'' correspond to the strips g' , g'' in Fig. 1. The construction of these strips and springs and coöperating parts is better shown in Fig. 14. As the posts or rods g' and g'' strike the rollers C^{42} the springs upon which the rollers are mounted are forced into contact with their respective contact strips c^{14} and d^{14} . The springs normally rest upon rod C^{29} covered preferably with ordinary soft rubber tubing. This rod is mounted at each end upon a pivoted arm C^{30} pivoted at C^{31} to the insulated support C^{28} . A screw C^{32} working in a threaded hole in the arm C^{30} and against the fixed plate C^{37} adjusts the position of the rollers with relation to the commutator rods.

The strips c^{14} and d^{14} are mounted upon an insulated support C^{40} which is connected at either end to a supporting spring C^{38} , which in turn is mounted upon the base C^{28} .

Through each spring C^{38} passes the shank of a screw C^{41} having its threaded end working in a threaded hole in a rigid support C^{39} . In this manner the proximity of the strips to the contact springs may be from time to time adjusted to allow for wear, and so forth. The function of these parts has already been described. The purpose of this figure is simply to show the preferred mechanical construction of the commutator outfit.

Upon a push button C^{10} is mounted a pin C^{50} playing in a slot C^{51} . There may be a separate slot C^{51} for each push button.

A portion of the keyboard is shown. The other parts are omitted as they are mere duplication.

There are intended to be 10 rows each containing 10 buttons, adapted to make 100 different combinations, as illustrated in diagram in Fig. 1, and wired as shown in that figure. Instead of a separate button for each number there may be one button only adapted to be inserted in any one of 100 holes. This button would be substantially then a plug. Such a plug should have a handle. The hollow in the lower end is necessary.

In Figs. 10 and 11 are shown some of the details of the construction of the transmitting switch apparatus, that is, the apparatus that controls the operation of a transmitting trunk terminal switch. In connection with Fig. 2 this apparatus has been described with relation to its electrical features, and now it is the purpose to set forth some of the preferred mechanical details. Some of the details, such as back stops and so forth are omitted because of the danger of rendering the drawings unintelligible from complexity.

Upon an arbor or shaft n^{12} which is mounted loosely or rigidly in end supports m^{27} are loosely mounted ratchet wheels m^{28} ,

n^{11} , m^{28} . These wheels are in electrical connection with the arbor, and are provided with suitable devices to prevent longitudinal motion thereon.

The ratchet wheel n^{11} for the circuit controller C^2 is shown in side view in Fig. 10. Upon its faces are projections n , n^{31} , n^{61} on one side, n^3 , n^4 on the other side, adapted to act on rollers n^7 mounted on contact springs n^4 , which are adapted to open and close the pairs of contacts n , n' , n^3 , n^4 , n^6 , n^8 , n^9 as shown in Fig. 2.

It is operated by a pawl m^6 in the direction of the arrow in its forward movement. The pawl m^6 is pivoted upon a lever r^7 which in turn is pivoted upon a suitable rigid support r^8 . The pawl m^6 is provided with a roller r^6 which engages with the tooth next below its normal position (shown), and forces the tooth upward under the influence of the weight r . The fixed roller r^4 acting on the arm r^5 of the pawl so guides the pawl that it may slide into position to engage a ratchet tooth, and when the tooth moves the wheel forward, is guided out of engagement with the tooth at the moment that the detent r^9 engages the next tooth for detention. The roller r^4 also prevents further useless upward movement of the pawl. This roller r^4 may permit the pawl to remain in the ratchet wheel and by a mechanical connection with the detent withdraw the pawl from the ratchet wheel while restoring, as indicated in Fig. 17. The weight r attached to the arm r^3 of the pawl tends to draw the pawl into engagement with the ratchet teeth, yet is strongly counteracted normally (or when the lever r^7 is not subjected to an outside or magnetic force) by the weight hung upon the lever r^7 .

The detent r^9 is mounted upon a suitable pivoting support m^{24} , and upon its heel m^{29} is provided with the insulating wedge m^{20} adapted to open contacts e^{31} and e^{33} , but this opening does not happen until the detent has been withdrawn to its extreme position by the magnet M^4 . This is due to the flexibility of the springs resting against the wedge m^{20} .

Upon the detent r^9 is mounted a slot m^{18} in which plays a rod r^{10} which in turn is carried by the armature m^{17} so that when the armature is drawn up by the magnet M^4 it withdraws the detent r^9 from the ratchet wheel, permitting the latter to return to its normal position. The slot m^{18} is sufficiently long to permit the detent to play over the ratchet teeth in their progress forward without affecting the rod r^{10} . The lifting of armature m^{17} by the magnet closes contacts m the function of these contacts being described in connection with Fig. 2, namely to hold the detent up until the wheel is returned to its normal position. The wheel is

provided with a pulley m^{23} upon which a restoring weight r is hung by means of a spring r' and cord r^2 .

Upon the pawl m^6 , see Fig. 11, is pivoted 5 a cross bar e^{34} , having loose engagements r^{11} with the ends of the armatures r^{12} , pivoted at r^{13} , and acting under the influence of magnets e^9 and e^7 . The armatures r^{12} have pawl movements m^8 , m^{11} , like that shown and described 10 in Fig. 10 for the controller C².

These pawl movements actuate the ratchet wheels m^{28} , upon each of which is mounted an arm m^9 and m^{11} adapted to sweep over and make contact with studs o^9 shown in 15 Fig. 2. In Fig. 11, only stud m^{68} is shown for convenience, on each switch m^{10} and m^{18} .

These ratchet wheels also have pulleys m^{28} with their cord springs and weights, r , r' , and r^2 . They are also provided with 20 detents m^9 and m^{19} and slots m^{18} in which works the rod r^{10} which withdraws the detents from their engagement with the ratchets. Upon the hub of the ratchet wheel n^{11} is a bar m^8 normally resting against the 25 upper side of the pivoted cross bar or link e^{34} . When this switching apparatus is operated, first the magnet e^9 is operated once, then the two magnets are operated alternately a determined number of times, to correspond 30 with the units and tens of the number signaled, and then the two magnets are operated simultaneously by the double rod g'' shown in Fig. 9. When magnet e^9 is operated the first time it draws down the pawl m^8 so that it engages with the proper tooth, and at the same time tips the link e^{34} so that the other end of the link, the right end in the figure, strikes against the bar m^8 , and the further movement of the link forces the 40 pawl m^6 downward so that it engages with the next tooth for operating purposes. When the current leaves the magnet e^9 the pawls lift upward again under the influence of their weights r , and advance the two ratchet

wheels one tooth, where they are held by the detents. The succeeding alternating impulses over these magnets and the corresponding sides of the metallic circuit advance the two wheels m^{28} and their switch 45 arms m^9 to their appropriate positions, but do not affect the pawl m^6 on account of the lost motion of the link connections r^{11} , and on account of the different position for the stop bar m^8 due to the advance of the ratchet wheel n^{11} to which it is rigidly connected. Finally however the impulses wind up with simultaneous ones, one in each magnet and together they again draw the pawl m^6 down sufficiently to engage with the next tooth of 50 the ratchet wheel n^{11} , thus advancing it another step into its third and final position. The condition of the contacts n , n' , n^3 , n^4 , n^5 and n^6 in these three positions have already been described in connection with Fig. 2,

and it is not necessary to repeat here. It is 65 enough to say that the projections upon the two faces of the wheel n^{11} should be so placed and gaged as to accurately perform their proper functions.

Upon insulating supports n^{18} are mounted 70 spring contacts m^{60} and m^{62} normally out of engagement with the flanges of the respective pulleys m^{28} on account of cuts or depressions at m^{61} and m^{100} respectively, but when the wheels are not in their normal position 75 these springs are in contact with the flanges. This closes the circuit to ground from the springs to the grounded supports m^{27} for the purpose of retaining the armature m^{17} in its active position until the wheels are all restored, as fully described in connection with 80 Fig. 2.

Upon insulating supports n^{15} are mounted the studs with which the contact springs n^{14} come into contact when operated by the circuit controlling ratchet n^{11} , to close the contacts of the controller. 85

Fig. 12 shows in side view a modified and preferred form of a transmitting trunk line switch already described in connection 90 with Fig. 2 and Fig. 8. Upon a shaft f adapted to be rotated under the influence of some kind of motor is rigidly connected a collar h^5 . This collar supports on the shaft the loosely mounted collar h^6 . Upon 95 the shaft f is also mounted rigidly a second sleeve h^7 and also the yoke h^8 of the coils i^2 as also shown in Fig. 18. Each armature yoke h^8 on the shaft is rigidly connected thereto, and acts as armature for the 100 magnet coils suspended below it. Each coil has a pole h^9 so shaped as to attract a ring armature h^2 .

The poles h^9 bear against a shoulder h^{10} rigidly connected to the loosely mounted 105 sleeve h^6 . The ring armature h^2 has an aperture sufficiently large to permit it to work up and down over the sleeve h^6 . When this ring armature is in its upper position shown, it impinges against the shoulder h^{10} and is thereby prevented from coming into contact with the poles h^9 of the magnet, which at the time may be rotating under the influence of the shaft and motor. The armature h^2 is pivoted at h^{11} upon an upright support h^{12} which is mounted upon the switch arm h^4 . This switch arm is rigidly connected to the sleeve h^6 . Connected to the armature h^2 is a catch h^3 normally engaged with a catch h^4 rigidly connected to the collar h^5 . When the armature h^2 is not attracted the catch h^4 drives the switch arm h^4 and all parts mounted thereon in the direction in which it rotates. When the catch h^3 leaves the catch h^4 the switch 115 arm h^4 stops its rotation, while the shaft f , the collar h^5 , the sleeve h^7 and the coils i^2 continue to rotate as long as they are in 120 125

fluenced by the motor. Upon the switch arm h' are mounted the contact springs i' , i'' , and i''' . The contact spring i'' is electrically connected with the switch arm, but the others are insulated therefrom except for the electrical connections. These springs play over the contacts e^{10} , e^{11} and e^{12} , whose functions have already been described. Mounted upon but insulated from the armature h^2 are two hollow rods h , one of which carries a bridging contact d^s , the other of which carries a similar contact c^s . These bridging contacts are pivotally mounted upon the bars h . The upper end of each of these contacts normally rests against stop h^{14} under the influence of springs h^{14} .

One end of each spring h^{14} is fastened to the bar around which it is coiled, and the other end of the spring is connected to the upper end of the contact mounted upon the bar. One bar h has an extension h^{15} which is guided by a properly formed guide piece h^{16} , which is mounted upon but electrically insulated from the switch board h^{17} . Mounted upon but electrically insulated from the bars h is a spring contact i' adapted to make connections with any one of a number of contacts e^{21} around the switch board.

Upon the support h^{12} are mounted two contact springs h^{18} adapted to make sliding contact with round annular rings h^{19} mounted upon coils i^2 of the magnet. These rings h^{19} form the terminals of the magnet coils. One contact spring h^{18} is connected by means of wires i to the contact springs i' and i'' . The other contact spring h^{18} is connected by means of wire i^s to contact spring i''' . A receiving trunk line switch is identical in construction with the transmitting switch shown in Fig. 12, except for the extra contact e^{10} , spring i^s , the construction of contacts e^{12} , and the electrical connections. This difference is well shown and described in connection with Fig. 2.

The circuit closing apparatus in Fig. 12 is shown in its active position. Normally the weight of the armature h^2 causes the catch h^3 to engage with the catch h^4 and the contacts c^s , d^s , and i' to be out of connection with their respective switch board contacts.

Fig. 13 shows a top perspective view of the apparatus shown in Fig. 12, or at least a part of this apparatus. The sets of contacts of the various subscribers are shown, and the serrated edge h^{16} which guides the end h^{15} so that the circuit closers c^s and d^s make proper connections with contacts c' and d' . It is also shown how the contact springs i' , i'' and i''' make connections with successive sets of contacts. The moment the springs leave one set of contacts they make electrical connections with the next set of contacts, so that the circuit closer h is

allowed considerable time to descend into place.

Upon the circuit closing bars h is shown the contact spring i' mounted upon insulating material. This spring i' is so adjusted that it will slide easily into place.

When the coils i^2 of this switch are energized over the circuit which has already been described, the armature h^2 is attracted by the poles h^9 causing the end h^{15} to strike the serrated guide h^{16} and steer the contacts c^s and d^s into such a position that they will make proper connections. In Fig. 12 it is shown how the two ends of the pivoted contacts c^s and d^s bear against their appropriate contact surfaces. By means of this construction these contact pieces have a frictional action in attaining their position and an equal amount of pressure is brought to bear upon each of the four pairs of contacts.

Normally these circuit controllers rotate with the shaft f . They may travel over the switch board at the rate of at least one rotation in three seconds. This speed has been found successful with solid core slow-acting magnets, but with quicker acting magnets a higher speed may be attained.

In Fig. 15, is shown a side view of the operator's cord switch, the front view being shown in Fig. 1. The lever P^2 is pivoted at P^8 , and is provided with a base P' , upon which the plug normally rests. A spring P' having bends P^9 working on the edge of the base tends to hold the base in its upper or lower position against the stops P^{10} . The operator may tip the lever P^2 into its upper or lower position, thereby altering the circuit connections as described in connection with Fig. 1.

The generator D^2 which supplies the current for restoring the system should supply a direct current preferably so toned down by electro-magnetic resistances and shunted by condensers as to be inaudible in the receivers by induction. It should be so toned as to be inaudible in the receivers in the manner well known to electrical engineers, by impedances and condensers, and the subscribers' bells α' so constructed as to respond thereto. The current may be direct, and the bells of the circuit breaking variety; or the current may be alternating of a periodicity below 16 pulsations a second, and with the intermissions between the pulsations less than one hundredth of a second in length. This nature of current I prefer. When developed from a dynamo, and its irregularities properly toned down, it acts satisfactorily both as calling and signaling current.

The operation of the exchange with a current supply of this character is as follows:

A subscriber desiring a connection takes down his receiver, thus permitting his

switch to ground the "b" side of his metallic circuit, and operating the first receiving switch whose contact springs pass over this subscriber's set of contacts. As these switches are spirally arranged with respect to the various sets of contacts of this subscriber, as shown in diagram in Fig. 1, but one receiving switch will operate.

This receiving switch making connection 10 with the calling subscriber's circuit closes a complete metallic circuit from the central station to the subscriber's station, including the subscriber's telephone set, the metallic circuit conductors of the subscriber, and the 15 metallic conductors of the receiving trunk line, between which is bridged the current generator CG, including a call annunciator 20 c^{12} . The current from the generator operates this call annunciator over the circuit described, calling the attention of the operator to this receiving trunk line.

The operation of the receiving switch has prevented the possibility of the calling subscriber's line being connected with any other 25 trunk line, and the telephone switch of the subscriber has closed the telephone circuit.

The operator, seeing the call annunciator display a signal, takes up the plug of the trunk line associated therewith and thus 30 cuts her telephone set into circuit, to find out the number of the called subscriber. Having learned the number she inserts the plug into the jack at her board of a transmitting trunk line running to the group to 35 which the called subscriber belongs, and depresses a button C^{10} of her commutator outfit shown in Fig. 9, causing the metallic conductors of the transmitting trunk line to make connection by means of the switch 40 apparatus shown in Figs. 2 and 11 with the metallic conductors of the called subscriber's circuit. This connection will take place only when the called subscriber is free.

When the operator has thus inserted the 45 plug in a jack and presses her commutator button, she tilts the switch p^2 into the third position already described, and leaves the lines to take care of themselves.

If the called subscriber is free the transmitting trunk line will immediately connect 50 itself thereto. The tilting of the operator's switch P^2 has cut the current from the receiving trunk line circuit just described and introduces it and the annunciator C^{13} into 55 the circuit of the transmitting trunk line as described, so that when the metallic circuit of the trunk line is connected to the called subscriber's line, this generator is in a complete metallic circuit, and the annunciator 60 c^{14} is again energized indicating to the operator that the called subscriber has responded. With the relay d^{14} it closes the metallic conductors of the transmitting trunk line to the metallic conductors of the 65 receiving trunk line connected to the calling

subscriber, thus completing a metallic circuit for conversation.

When the current traverses the circuit of the called subscriber it operates his call bells as long as his telephone is not switched for 70 use. When he answers the call this current is inaudible in his telephone.

The closing of contacts c^{12} and d^{12} by the annunciator also closes the circuit of the generator CG to the circuit of the calling 75 subscriber again, and if he has dropped his telephone and returned to work leaving the contacts a^{16} and a^{17} closed to each other, rings his call bell a' informing him that his order has been fulfilled and that he has 80 been connected to the called subscriber.

The circuit may be supervised by the operator who has established these connections by looping or bridging her telephone set into the circuit as already described. 85

The pulsations of the alternating current CG are preferably so slow as not to cause annoyance to the called subscriber. Five or six pulsations to the second is quite sufficient for the purpose of calling and signaling. 90

When conversation is over, and the subscribers have no further use for the metallic circuit which has been described the subscribers hang their telephones upon their switches thereby grounding the "a-c" side 95 of their metallic circuit. This ground connection may be effected by either subscriber or by both. That is, when the "a" side of the circuit is grounded by the first subscriber who hangs up his telephone, or by both 100 when they both hang up their telephones together, the relays M^4 and M^5 are operated as has been described with relation to Fig. 2, and the switches at the sub-central or, in other words, the transmitting and receiving 105 trunk line switches, are released, and the connection between the subscribers' metallic circuits and the trunk line metallic circuits is opened by the disconnected contacts c^3 and d^3 thereby opening the circuit of the 110 generator current from CG, and releasing the flap of the annunciator c^{13} , indicating to the operator at the central station that the trunk lines are no longer in use. She then withdraws the receiving trunk line 115 plug from the jack of the transmitting trunk line jack, and returns the plug to its normal resting place on the insulated support P' , at the same time pressing this support back to its normal position shown in connection 120 with the receiving trunk line R^2 .

The relay M^5 opens the contacts e^{18} of the receiving trunk line switch.

The restoring circuit operates magnet M^4 which, as will be seen in Fig. 11, releases 125 the apparatus controlling the transmitting switch. The contacts n^4 are opened by the circuit controller C^2 thus opening the circuit of the coils i^2 of the transmitting switch, whereby that switch resumes its normal po- 130

sition, and if the shaft f is rotating, it continues to rotate with it.

The speed with which a connection is established by my system depends upon the speed 5 of rotation of the transmitting and receiving switches, and the speed with which the apparatus controlling transmitting switches is operated by the operator's commutator outfit.

10 As the first one of the spirally arranged receiving trunk switches closes a subscriber's circuit to central, this circuit is closed almost instantaneously. When the exchange is at its busiest time, this connection cannot 15 be delayed more than two seconds at the outside, so that when a subscriber takes down his telephone from its switch, the connection to central is established, and the call annunciator operated before the receiver 20 reaches his ear. The operator's telephone is cut in by her taking up the trunk line plug, and this is done in the usual manner, except that it is done more quickly than when the operator has to insert a plug into the jack 25 of a calling subscriber. This operation is saved by my system. After inserting the plug into the jack of the proper transmitting trunk line, and at a glance she can see what trunk line is not busy, she presses down one 30 of her commutator buttons C^{10} and after one or two seconds tilts the handle of her switch P^2 . This is plenty of time for the apparatus to be operated for controlling the transmitting trunk switch, for one second I 35 find is the outside limit for the maximum number of impulses to be sent over each side of the metallic circuit, so that the time which has been consumed between the moment when the subscriber took down his receiver 40 to the moment when the operator has finished her part in establishing the desired connection is at the outside not more than four seconds, and is generally not more than two or three seconds. The operator's 45 share of this time is still less.

If the called subscriber is free the connection to his line will be almost instantaneous, never more than two seconds late, and this connection is indicated to the operator. 50 If, during the busy hours of the exchange, the operator has other connections to establish she can at once turn her attention to them. If the called subscriber is busy, the indicator will not operate, and she will know 55 that the connection has not been established. She can then loop or bridge her telephone into the circuit and tell the calling subscriber that he may drop his telephone, and that he will be called when the called subscriber is 60 free. The calling is automatically effected without further attention of the operator when the called subscriber is "free". If the indicator tells her that the connection has not been established after some time, and the 65 trunk line is needed, the operator may close

a pair of extra contacts c^{10} and withdraw the plug from the jack, leaving the trunk lines and trunk switches in their normal position.

It will be seen that my invention saves a 70 great deal of time on the part of the central operator.

For an exchange of ten thousand subscribers having a single central station, each board of the systems now in use requires a 75 jack for each subscriber and about one hundred annunciators. A dozen or fifteen clearing-out annunciators are also used.

In my exchange, the jacks are reduced from 10,000 in number to 1200 or 1500, the 80 calling annunciators are entirely omitted, and about 12 or 15 annunciators used for both calling and clearing-out.

In systems now in use, 24 to 30 plugs are required for each operator. In my system 85 the plugs are reduced to one half the number.

In systems now in use, the metallic circuits of the above exchange would be 10,000 in number, and each one would reach from the 90 subscriber's station to the central office. In my system these circuits are reduced to about 1000 to 2500 in number for the greater part of the distance.

To obtain these advantages requires that 95 each operator shall have a commutator outfit like that shown in Fig. 9 and that from 10 to 25 trunk line switches be located at some outlying points in proximity to groups of subscribers. That is, each group of 100 subscribers shall have a few switches in some place in their locality. These are the only additions required by my system.

It is obvious that single circuit lines may be organized into an exchange of this kind, 105 and that by slight alterations two or more subscribers may use the same individual circuit. For the latter arrangement suitable automatic calls should be provided under the control of the operator.

In the following claims I shall make use of the term "side switch" by which it is to be understood that a commutator or equivalent device for controlling and directing the application of current to one or the other actuating elements of the main switch, as for example the commutator used in combination with the units and tens elements hereinbefore described.

For convenience I may also make use of 120 the expressions "double element selection" and "two-element selection". By this I mean that the selection of a unit in a given group is made by double selection of the group and the unit in the group. While my switch hereinbefore described is specifically 125 a single motion switch, it is conceivable that the same general method of functioning might be applied to what is known in the art as the two-motion switch, viz. one in which 130

the switch arms move in two different directions, as vertically and horizontally.

I do not want to limit the use of my invention to the exact apparatus or circuits shown, for it is obvious that wide variations may be made from them and still the general results obtained.

What I claim and desire to secure by Letters Patent is:—

- 10 1. In a grouped multiple switch board exchange, groups of subscribers' circuits, receiving trunk lines having automatic switching devices for each group controlled from the subscribers' stations, transmitting trunk lines having automatic switching devices for each group controlled from the central office, adapted to be connected to said subscribers' circuits, non-interference apparatus to prevent more than one trunk line 70 from being connected to the same subscriber's circuit at the same time, plugs connected to said receiving trunk lines distributed among the boards, jacks at each board connected to each of said transmitting trunk lines for the purposes of connecting, and a test circuit associated with each transmitting trunk line to indicate its "free" or "busy" condition at all the boards.
- 20 2. In a grouped multiple switch board exchange, groups of subscribers' circuits, receiving trunk lines having automatic switching devices for each group controlled from the subscribers' stations, transmitting trunk lines having automatic switching devices for each group controlled from the central office, adapted to be connected to said subscribers' circuits, plugs connected to said receiving trunk lines distributed among the boards, jacks at each board connected to each of said transmitting trunk lines for the purposes of connecting, and a test circuit associated with each transmitting trunk line to indicate its "free" or "busy" condition at all the boards.
- 30 3. In a grouped multiple switch board exchange, groups of subscribers' circuits, receiving trunk lines having automatic switching devices for each group controlled from the subscribers' stations, transmitting trunk lines having automatic switching devices for each group controlled from the central office, adapted to be connected to said subscribers' circuits, plugs connected to said receiving trunk lines distributed among the boards, jacks at each board connected to each of said transmitting trunk lines for the purposes of connecting, and a test circuit associated with each transmitting trunk line to indicate its "free" or "busy" condition at all the boards.
- 40 4. In a grouped multiple switch board exchange, groups of subscribers' circuits, receiving and transmitting trunk lines having automatic switching devices for each group, adapted to be connected to said subscribers' circuits, plugs, one for each receiving trunk line, distributed among the boards, and spring jacks, one for each transmitting trunk line at each board, and a test system to prevent an established connection between two trunk lines from being interfered with.
- 50 5. In a grouped multiple switch board exchange, groups of subscribers' circuits, receiving trunk lines having automatic switching devices for each group controlled from the subscribers' stations, transmitting trunk lines having automatic switching devices for each group controlled from the central office, adapted to be connected to said subscribers' circuits, non-interference apparatus to prevent more than one trunk line from being
- 60 connected to the same subscriber's circuit at the same time, plugs connected to said receiving trunk lines distributed among the boards and jacks at each board connected to each of said transmitting trunk lines for the purposes of connecting.
- 70 5. In a grouped multiple switch board exchange, groups of subscribers' circuits, receiving trunk lines having automatic switching devices for each group controlled from the subscribers' stations, transmitting trunk lines having automatic switching devices for each group controlled from the central office, adapted to be connected to said subscribers' circuits, plugs connected to said receiving trunk lines distributed among the boards, and jacks at each board connected to each of said transmitting trunk lines for the purposes of connecting.
- 80 6. In a grouped multiple switch board exchange, groups of subscribers' circuits, receiving trunk lines having automatic switching devices for each group controlled from the subscribers' stations, transmitting trunk lines having automatic switching devices for each group controlled from the central office, adapted to be connected to said subscribers' circuits, non-interference apparatus to prevent more than one trunk line from being connected to the same subscriber's circuit at the same time, and switching apparatus at each board for connecting a receiving and a transmitting trunk line together.
- 90 7. In a telephone exchange system, a plurality of lines to be interconnected and central station means for interconnecting them comprising primary selector switches having line test terminals, line relays controlled over the lines to place testing potential on said terminals, and means controlled by a switch 100 when it finds the line to mechanically disable the line relay.
- 100 8. In a telephone exchange system, a plurality of lines to be interconnected, and central station means for interconnecting them comprising primary selector switches containing line terminals and test terminals and arranged to make initial connection with a calling line, a line relay arranged when energized to place test potential on 110 the test terminals, and means to disable the line relay and thereby to remove said test controlled through a special bank of contacts on the primary selector switch.
- 110 9. In a telephone exchange system, a plurality of lines to be interconnected, and central station means for interconnecting them comprising primary selector and connector switches containing multiples of the line terminals and line test terminals, a line 120 relay normally maintaining test potential on the test terminals of the connector switches but arranged when energized to remove test potential from connector test terminals and apply the same to the test terminals of the 130

primary selectors, together with means controlled through the primary selectors to remove the test potential applied by the line relay to them, but to prevent the reapplication of test potential to the connector switches.

10. In a telephone exchange system, a plurality of lines to be interconnected and central station means to interconnect them comprising primary selector and connector switches containing multiples of the line terminals and a pair of agencies arranged to control the test conditions of each line, the one normally maintaining idle test potential on test terminals in the connector switches and operable from the line to remove said test potential from the connector switches and apply the same to corresponding terminals in the primary selectors, and 20 the other of said agencies operable through both the primary selector and connector switches to remove test potential from the primary selector switches if applied thereto, and to remove from or prevent the application of test potential to the connector switches.

11. In a telephone exchange system, a plurality of lines to be interconnected, and central station means for interconnecting them comprising primary selector switching means, and a pair of agencies for each line controlling the test conditions thereof, the one controlled over the line to apply test potential to test terminals in the primary selector switching means, and the other acting upon the first agency to disable the same and itself controlled through special contacts in the primary selector switching means, separate from both the line terminals and the 40 test terminals, and arranged when energized to effect the removal of the test potential applied by the first agency.

12. In a telephone exchange system in combination, a plurality of lines to be interconnected, automatic switches for interconnecting them, a circuit for starting the operation of said switches closed over one side of the subscriber's line, means located entirely at the central office for continuing the 50 operation, releasing means for said switches, and a control circuit therefor closed over the other side only of the subscriber's line.

13. In a telephone exchange system, a plurality of lines to be interconnected, automatic switches for interconnecting the same, a line relay in a grounded circuit including one side of the subscriber's line and arranged when the subscriber calls to start the operation of said switches, means located entirely at the central office for continuing the 60 operation, releasing means for said switches and a grounded circuit therefor including the other side only of the subscriber's line and controlled from the subscriber's station.

65 14. In a telephone exchange system, sub-

scribers' lines, central station means including automatic connector switches for interconnecting said lines, said switches being arranged to continue the line testing operation indefinitely but under the control of the 70 subscribers, and signals at the calling subscribers' stations actuated when the testing operation of the switch is completed whereby calling subscribers are apprised of the completion of connection wanted.

75 15. In a telephone exchange system, subscribers' lines, automatic connector switches for effecting a selection of called lines, releasing means for the switches operated independently of the testing operation of the 80 switch and controlled by an operator, whereby the switch may continue its testing operation indefinitely, and means at calling subscribers' stations actuated upon the completion of the testing operation to advise calling subscribers thereof.

85 16. In a telephone exchange system, subscribers' lines, central station means for interconnecting them, comprising automatic connector switches arranged to select and 90 test called lines, releasing means for said switch controlled independently of the testing operations thereof and under the control of the subscribers, whereby the testing operation may continue indefinitely, and indicators at the calling subscribers' stations the circuits of which may be closed by the calling subscribers to render them responsive to the completion of the connection with called subscribers.

95 100 17. In a telephone exchange system, subscribers' lines, central station means for interconnecting them including automatic connector switches arranged to select and connect with called subscribers' lines, together 105 with indicating means at the subscribers' stations arranged to be placed at the will of the calling subscriber in a circuit closed upon the completion of connection with a called subscriber, whereby a calling subscriber is apprised of the completion of the connection if he so desires.

110 18. In a telephone exchange system, subscribers' lines, automatic connector switches for completing connection to called lines, 115 and automatic ringing means including a relay at the central station energized when ringing current is applied to the called line and when energized to apply ringing current to the calling line, together with a signal device at the subscriber's station responsive to ringing current and arranged to be connected in circuit with the line at the will of the subscriber independently of the receiver hook whereby calling subscribers may 125 receive indication of the connection with a called subscriber's line.

120 130 19. In a telephone exchange system, subscribers' lines, automatic switching apparatus for interconnecting said lines, an 130

operator's control device for directively controlling said switches, manual trunking means for effecting connections between said automatic switches, and means to connect and disconnect said operator's sending device from the automatic switches controlled in the operation of said manual switching means.

20. In a telephone exchange system, subscribers' lines, automatic switches for interconnecting the same, central station call indicating devices, operator's switch control means, central station ringing means, and manual means to connect calling lines with 10 said automatic switches and through the operation of which the aforesaid indicating, ringing and switch control means are exclusively controlled.

21. In a telephone exchange system, a 20 plurality of subscribers' lines, automatic switching apparatuses adapted for double element selection, for interconnecting them, each switching apparatus including a side switching device, link circuits connecting 25 with said automatic switching apparatuses, means responsive to control over one side of said link for producing one selection of the switching apparatus, means responsive to control over the other side of said link for 30 effecting the other selection thereof, and means responsive to control over both sides of said link simultaneously for effecting operation of said side switching device.

22. In a telephone exchange system, a 35 plurality of subscribers' lines, two element selection automatic switching apparatuses for interconnecting them, each switching apparatus including a side switching device, link circuits connecting with said automatic 40 switching apparatus, means responsive to control over one side of said link for producing one selection of the switching apparatus, means responsive to control over the other side of said link for effecting the 45 other selection thereof, means responsive to control over both sides of said link simultaneously for effecting operation of said switching device, and control means for said switching apparatuses arranged to be associated with the link circuits and comprising 50 two digital sets of individually and independently characterized control circuits together with means to connect the circuits of the sets with the opposite sides of said link 55 circuit alternately at times and simultaneously at other times.

23. In a telephone exchange system, subscribers' lines, automatic switches for effecting the interconnection of the same, and 60 control means for said switches comprising two digital sets of individually and independently characterized control circuits therefor arranged in rectangular coördination with each other together with a unitary 65 device for simultaneously associating with

said switches a pair of the coördinated circuits for the control thereof.

24. In a telephone exchange system, lines, automatic switching means to interconnect the same, and control means therefor comprising two digital sets of control circuits therefor terminating in rectangularly coördinated conductor sections, together with a unitary device for interconnecting a pair of the coördinated conductors at a point of 70 intersection thereof and the pair together to said automatic switches whereby the associated control circuits may govern the same.

25. In a telephone exchange system, lines, and two motion automatic switching apparatuses for interconnecting the same, a side switch, actuating means to produce each motion of the switching apparatus, and means arranged to operate the side switch upon the simultaneous energization of both actuating 75 means.

26. In a telephone exchange system, lines, and automatic switching apparatuses for interconnecting them comprising connector switches arranged to connect with the terminals of a wanted line, tens and units step-by-step switches arranged to select the line terminals with which the connector switch ultimately makes contact, a side switch, means to impart a step-by-step motion thereto, actuating means for each of said connector, tens, and units switches controlled from said side switch, and releasing means for the tens and units switches also controlled by said side switch.

27. In a telephone exchange system, lines, two motion automatic switching apparatuses for interconnecting them, actuating means for driving each of said switching apparatuses through each of its motions, releasing means therefor, and a side switch controlling both the actuating and releasing means and itself actuated through the two motions of the switching apparatuses.

28. In a telephone exchange system, lines, and automatic switching apparatuses for interconnecting the lines, each apparatus comprising a rotatably driven connector switch containing line terminals and test terminals, tens and units step-by-step switches controllable over a link circuit to put test potential on the test terminals corresponding with the line terminals with which contact is ultimately made by said connector switch, and a side switch device controlling the rotation of said connector switch and the connection of the terminals of said tens and units switches thereto.

29. In a telephone exchange system, lines, automatic switching apparatuses to interconnect the same, each of said switching apparatuses comprising a rotatably driven connector switch containing line terminals and test terminals, together with tens and units step-by-step switches having terminals con- 125

connected with said test terminals and controlled over the link circuit of said switch to impose test potential on the test terminals thereof.

- 5 30. In a telephone exchange system, lines, automatic switching apparatuses to inter-connect the same comprising rotatably driven connector switches containing line terminals arranged in groups of ten according
10 to the number thereof, a tens test terminal coextensive with the units terminals of each group, and units test terminals corresponding to the individual terminals of the groups

also arranged in groups associated with the corresponding test terminals, together with means controlled over the connector link circuit for imposing test potential on a units terminal and a tens terminal designating the line called.

15 In witness whereof I hereunto sign my name in the presence of two witnesses:

MYRON F. HILL.
